US00D870069S

(12) **United States Design Patent** (10) **Patent No.:** **US D870,069 S**
Hu (45) **Date of Patent:** **** Dec. 17, 2019**

(54) **HEADPHONES**

(71) Applicant: **SHENZHEN QIANHAI PATUOXUN NETWORK AND TECHNOLOGY CO., LTD**, Shenzhen (CN)

(72) Inventor: **Zaihui Hu**, Shenzhen (CN)

(73) Assignee: **SHENZHEN QIANHAI PATUOXUN NETWORK AND TECHNOLOGY CO., LTD**, Shenzhen (CN)

(**) Term: **15 Years**

(21) Appl. No.: **29/705,279**

(22) Filed: **Sep. 11, 2019**

(51) **LOC (12) Cl.** **14-01**

(52) **U.S. Cl.**

USPC **D14/206**; D14/226

(58) **Field of Classification Search**

USPC D14/206, 226, 205; D29/112; 2/209; 181/129, 130, 135; 379/430, 431; 381/380, 381, 374; 455/90.3, 575.1, 455/569.1

CPC H04R 25/00; H04R 1/1016; H04R 1/1066; H04R 5/033; H04R 5/0335; H04R 1/105; H04R 19/04; H04R 17/02

See application file for complete search history.

Primary Examiner — Paula Allen Greene

(57) **CLAIM**

The ornamental design for headphones, as shown and described.

DESCRIPTION

FIG. 1 is a perspective view of headphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The broken lines in the drawings depict portions of the headphones that form no part of the claimed design.

1 Claim, 9 Drawing Sheets
